UNITED STATES PATENT OFFICE.

LESTER R. WELLMAN, OF CHICAGO, ILLINOIS, ASSIGNOR TO FRIEDELEY-VOSHARDT CO., OF CHICAGO, ILLINOIS, A CORPORATION OF ILLINOIS.

DESIGN FOR A RING FOR SUPPORTING GLASS LIGHTING-BOWLS.

49,633.

Specification for Design.

Patented Sept. 5, 1916.

Application filed July 22, 1916. Serial No. 110,810. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Ring for Supporting Glass Lighting-Bowls, of which the following is the specification, reference being had to the accompanying drawing, forming part thereof.

Figure 1 is a side elevation of a ring for supporting glass lighting bowls, showing my new design. Fig. 2 is a top or plan view of the same.

I claim:

The ornamental design for a ring for supporting glass lighting bowls, as shown.

LESTER R. WELLMAN.
